UNITED STATES PATENT OFFICE.

FRANZ LÖSEL, OF BRUNN, CZECHOSLOVAKIA.

STEAM-TURBINE CONSTRUCTION.

Application filed August 26, 1924. Serial No. 734,354.

To all whom it may concern:

Be it known that I, FRANZ LÖSEL, a citizen of Czechoslovakia, residing at Brunn, Czechoslovakia, have invented certain new and useful Improvements in Steam-Turbine Construction, of which the following is a specification.

This invention relates to turbine constructions of the elastic fluid type.

10 The object of the invention, generally stated, is a turbine construction in which the leakage losses are substantially reduced as compared with prior constructions and which is of durable character and may be 15 economically manufactured. I effect this purpose by a novel combined rotor and enclosing casing construction having a reduced leakage clearance space and permitting the use of comparatively thin rotor 20 blade covering rings without impairing the structural strength.

For better understanding of the invention, reference may be had to the accompanying drawings wherein

25 Fig. 1 is a partial sectional view through a turbine embodying my invention, and

Fig. 2 is a similar view illustrating a modified construction.

Referring to Fig. 1, I have indicated a 30 rotating bucket blade or element *a* of a rotating disc or wheel having therearound a shrouding or covering ring *b*. A portion of the enclosing casing or carrier body for the guide blades is indicated at *d*, and the stationary guide nozzles on opposite sides of the rotating bucket *a* are illustrated diagrammatically and indicated by the letter *g*. The shrouding or cover ring *b* is indicated of 35 very small depth or thickness, and is connected with the blades *a* and secured in place by rivets of a character indicated by the letter *c*, the latter being substantially centrally disposed between the opposite edges of the ring. The ring *b* is of the thin 40 character and construction indicated to minimize the centrifugal forces and to reduce the thrust losses due to the thrust of the steam upon the entering peripheral edge of the ring *b*, and in order to permit 45 only a partial counter sinking of the rivet heads *c* into the outer surface of the thin ring *b* and to avoid the weakening of the structure due to full counter sinking, I form the interior of the casing or part *d* with an 50 interior enclosing surface so as to form a very small clearance *e* on the left hand of

the rivets *c* and in the front side of the ring but a larger clearance *f* for the remainder or trailing portion of the width of the blades *a*, the clearance *f* being of sufficient depth 60 to safely clear the protruding rivets *c* which secure the ring *b* in position. The clearance *e* is very small and is just large enough to clear the shrouding ring *b* under all conditions of operation, whereby the leakage of 65 steam through the rotating canals, about the periphery of the ring *b* is reduced to a practical minimum. Moreover, due to the thinness and small depth of the enclosing ring *b*, the losses from the thrust and impingement of the steam upon the axially disposed edge thereof is reduced to a minimum, while the ring *b* is secured firmly in position by the non or partly countersunk rivets 70 *c* whose heads are cleared by the machined 75 out portion of the casing part *d* indicated by the clearance *f*. In the embodiment of my invention exhibited in Fig. 1 the ring *b* is indicated of substantially equal depth throughout its width and the clearances *e* 80 and *f* may be provided by machining the the interior enclosing surface wall of the enclosing member or casing *d* at two different diameters indicated by *D*¹ and *D*², the diameter *D*² being sufficiently larger than 85 the diameter *D*¹ to clear the outwardly projecting or protruding rivet heads *c* under all conditions of operation.

In the example of my invention exhibited in Fig. 2 the trailing part of the ring *b'* is 90 of uniform depth or thickness from the right to a point just past the protruding rivet heads *c*, but from that point to the left hand or leading edge the ring *b'* is made of increasing depth at an angle *x* to the horizontal, and the casing *d* is conically machined off at an angle to the horizontal corresponding to the angle *x*, so as to form the clearance *e* of very small depth so as to reduce the tendency of the elastic fluid to leak 95 therethrough. A clearance *f* to the right is indicated of the general character shown in Fig. 1 for clearing the rivet heads *c*. Arrow *i* indicates the direction of the steam trying or tending to escape up past the bucket *a* and through the small clearance *e*, and according to this modification of the invention 100 a pumping effect is present within clearance *e* due to the gradually increasing outer diameters of the ring *b'* from the rivet heads *c* to the front of the blade edge. This pumping effect, being in opposition to 105 110

the flow of the working steam, tends to counteract and compensate for the tendency of the steam to flow in the opposite direction indicated by the arrow I. The clearance or leakage loss, therefore, is reduced both because of the small depth of the clearance e , and because of the opposite flowing tendencies of the steam from opposite sides around the peripheral edges and the outer surface of the ring b .

In both the modifications of my invention exhibited herein, therefore, the usual clearances f corresponding to the depth of the rivet heads c characteristic of former constructions are reduced to an effective clearance e on the entering side of the steam and up to the rivet heads c , thereby substantially diminishing clearance losses. Moreover, by means of the wedge or conical shaped construction of the front edge of the ring b' the leakage loss is further reduced by the counter pumping or suction effect within the clearance e opposite to the flow of the working fluid. Moreover, the construction is of simple character and may be cheaply and economically manufactured.

Having thus described my invention, what I claim as new and desire to secure by Letters Patent is:

1. A steam turbine construction comprising a rotating blade element with a cover or shrouding ring around the periphery thereof which is anchored thereto by means of securing devices projecting above the outer surface of the ring and an enclosing casing or part forming with said ring radial clearances of unequal depth on opposite sides of the protruding securing devices, the clearance of the lesser depth being relatively shallow but of considerable length between the leading or entering edge and said protruding securing devices and the other clearance being of sufficient depth to clear said protruding securing devices and extending to the other edge of said ring.

2. In a turbine of the axial flow type, a rotating blade element having a shrouding enclosing ring passing around the periphery thereof with anchoring rivets securing said ring to the rotating element at points removed from the opposite edges thereof and having heads protruding above the outer surface thereof and an enclosing casing or part for said rotating element forming with said shrouding ring a radial clearance on the trailing edge of the ring of sufficient depth to clear the protruding rivet heads, and a clearance on the other side or entering edge of the ring of smaller depth forming a relatively shallow and long clearance between said entering edge and rivet head and not sufficient to clear the rivet heads.

3. In a turbine construction of the character set forth in claim 1 in which the interior of the casing is formed of different di-

ameters to form the unequal clearances on the opposite sides of the head ring.

4. In a steam turbine of the axial flow type, rotor blades, a head ring connected with said rotor blades and having a portion wedge-shaped in section with its inclined surface tapering inwardly from the adjacent edge of the ring, and an enclosing stationary part having a conical interior portion shaped to form a relatively small clearance with said head ring.

5. In a steam turbine a rotating blade element having a cover or shrouding ring secured thereto by slightly protruding attaching devices at points removed from the opposite edges of the ring and a turbine casing or part enclosing the ring and forming therewith a clearance on the trailing side of the ring of sufficient depth to clear the protruding parts of the securing devices and said ring and casing being formed with a clearance of smaller depth on the leading side of the ring and outwardly inclined from a point adjacent the protruding securing devices for the purpose set forth.

6. In a steam turbine, a combined rotating blade element and enclosing casing element construction forming therebetween on the outer periphery of said blade element a relatively small clearance axially inclined inwardly from the outer periphery of the entering edge of said blade element to a line between said entering and leaving edges, for the purpose set forth.

7. In a steam turbine, a combined rotating blade element and enclosing casing element construction forming therebetween on the outer periphery of said blade element a clearance parallel to the axis and extending over part of the blade element width and an inclined clearance of smaller depth for the remainder of the width.

8. In a turbine of the axial flow type, rotor blades, a head ring connected therewith by means including rivet heads engaging the outer surface of the head ring, and a rotor enclosing structure forming with the head ring a relatively shallow and relatively long clearance between the edge of the head ring and the rivet heads and beyond said shallow and relatively long clearance a clearance of sufficient depth to clear the rivet heads.

9. In a turbine of the axial flow type, rotor blades, a head ring connected therewith by means including rivet heads engaging the outer surface of the head ring, and an integral rotor enclosing part forming with the head ring a relatively shallow and relatively long clearance between one edge of the head ring and the rivet heads and beyond said shallow and relatively long clearance a clearance of sufficient depth to clear the rivet heads.

10. In an elastic fluid turbine, a rotor

blade element with a cover at the outer periphery thereof, and a casing element construction enclosing said cover and forming therewith a relatively small clearance axially inclined inwardly in the direction of the steam flow for part of the width of the cover and counteracting the leakage fluid flow.

11. In an elastic fluid turbine, a rotor blade element with a cover at the outer periphery thereof, and a casing element construction enclosing said cover and forming therewith a relatively narrow clearance axially inclined inwardly in the direction of working fluid flow from the fluid entrance edge towards a line intermediate the edges of the cover and counteracting the leakage fluid flow, and a somewhat larger clearance on the outer periphery of the leaving edge of said blade element.

12. In an elastic fluid turbine, a rotor blade element having a cover at the outer periphery thereof, and a stationary portion enclosing said cover and forming therewith at the outer periphery thereof a relatively shallow and long clearance axially inclined in the direction of the working fluid flow and counteracting the leakage fluid flow, and behind said shallow clearance a greater clearance at the leaving side of said cover.

13. In an elastic fluid turbine, a rotor

blade element having a cover at the outer periphery thereof and a stationary casing portion having at its inner surface an inwardly inclined surface part enclosing said cover and forming with the outer periphery of said cover a relatively shallow and long clearance inclined inwardly from its entrance and serving as combined tightening means and, during operation, compressing and pumping means also, counteracting the fluid leakage at the entrance of the clearance and reducing the leakage loss between said stationary portion and rotating element.

14. In an elastic fluid turbine, a rotor blade element having a cover at the outer periphery thereof, and a stationary portion enclosing said cover and forming with the outer periphery thereof at the entrance side of said element a relatively shallow and long clearance axially inclined inwardly in the direction of the working fluid flow to act, during operation, as tightening means and pumping means counteracting the fluid leakage flow, and another somewhat larger clearance at the periphery of the leaving side of said element.

In testimony whereof I have signed my name to this specification.

FRANZ LÖSEL.
